UNITED STATES PATENT OFFICE.

WALTER L. CULVER, OF ST. LOUIS, MISSOURI.

DESIGN FOR A FURNACE.

SPECIFICATION forming part of Design No. 21,467, dated April 19, 1892.

Application filed March 21, 1892. Serial No. 425,859. Term of patent 14 years.

To all whom it may concern:

Be it known that I, WALTER L. CULVER, a citizen of the United States, residing at St. Louis, in the State of Missouri, have invented and produced a new and original Design for Furnaces, of which the following is a specification, reference being had to the accompanying drawing, forming part thereof.

The drawing is a perspective view showing my design.

The leading features of my design consist of a cylinder-like portion 1, mounted upon the base 2, and at the bottom or lower portion of which is a rounded body 3, having necks or

extensions 4, the two outside necks or extensions having inwardly-curved upper portions 5 and the top of the intermediate neck or portion having an upwardly-curved top 6. At the front of the body 1 are rectangular portions 7, as shown in the drawing.

I claim as my invention—

The new design for a furnace, herein shown and described.

WALTER L. CULVER.

In presence of—

E. S. KNIGHT,
A. M. EBERSOLE.
